UNITED STATES PATENT OFFICE.

HANS J. ZIMMERMANN, OF PHILADELPHIA, PENNSYLVANIA, ASSIGNOR TO SCHUTTE AND KOERTING COMPANY, OF PHILADELPHIA, PENNSYLVANIA, A CORPORATION OF PENNSYLVANIA.

HEAT-EXCHANGE APPARATUS.

Application filed July 14, 1922. Serial No. 574,927.

To all whom it may concern:

Be it known that I, HANS J. ZIMMERMANN, a citizen of Germany, and a resident of Philadelphia, in the county of Philadelphia, 5 and State of Pennsylvania, have invented an Improvement in Heat-Exchange Apparatus, of which the following is a specification.

My invention relates to heat exchange apparatus, particularly apparatus which is 10 employed for effecting an interchange of heat between fluids such, for instance, as steam, and liquids, where air is heated by steam or liquids are cooled by air, etc.

The efficiency in operation of apparatus of 15 this character is dependent upon various factors such as the velocity of flow of the two media between which the interchange of temperature is being effected; the area of the surfaces of the walls which separate the two 20 media; the length of the passageways through which the media flow; and other factors which need not be mentioned.

In order that such apparatus shall operate efficiently it is necessary that the various 25 parts thereof shall be properly proportioned with respect to each other and with respect to the work to be done which heretofore has necessitated the designing of special apparatus for each installation to meet the 30 special conditions involved in each case. The designing, building and installing of such apparatus has involved relatively large expense.

The principal object of my invention is to 35 standardize the parts or elements entering into the construction of heat exchange apparatus so that the said parts may be united and combined to construct an apparatus of the size and capacity desired without the necessity 40 of designing and creating a new design of a character to satisfy the conditions to be met thus avoiding expense and delay. By the provision of standardized parts to be employed in the construction of heat exchange 45 apparatus, manufacturers needing to employ such apparatus may keep in stock, or purchase as needed, the parts necessary to construct apparatus of the capacity required.

A further object of the invention is to provide constituent standardized parts which are adapted to be employed in the construction of such apparatus of a character such that they may be readily assembled into a unitary structure.

A still further object is to provide an apparatus which may be composed of a plurality of units which may be readily assembled or disassembled if desired. 55

Without attempting at this time to point out other objects and advantages incident to my invention I shall now proceed to a detailed description thereof in which reference will be made to the accompanying drawing in which one convenient form of embodiment of apparatus is depicted; but it will be understood that the invention is susceptible of embodiment in other forms of construction than that shown and that changes in the details of construction may be made 60 within the scope of the claims without departing from the scope of the said invention. 65

In the drawings:

Fig. 1 is a view partly in vertical section and partly in side elevation of an apparatus embodying my invention shown in position 70 within a channel or passageway through which one of the heat or temperature interchange media is adapted to flow; 75

Fig. 2 is a vertical sectional view taken on the line 2—2 of Fig. 1, one of the units 80 of the apparatus being shown in elevation;

Fig. 3 is a view partly in plan and partly in horizontal section of one of the terminal or head portions of the apparatus; and

Fig. 4 is a top plan view of a portion of 85 the casing within which the apparatus is situated.

Referring to the drawings: 1 designates the top and bottom and 2 the side portions 90 of a part or section of the casing rectangular in cross section within which the apparatus embodying my invention is situated and through which one of the media involved in the heat exchange operation is adapted to 95 flow. The apparatus embodying my invention may comprise one or a plurality of what I shall call heat exchange units which are adapted to be connected together in the manner which will be described hereinafter. Each unit is composed of a plurality of 100 standardized parts which are adapted to be united and combined and connected together, also as will be described hereinafter.

Each unit in the construction shown 105 comprises two series or rows of tubes 3 arranged in parallel and staggered relation with respect to each other as shown in Fig. 3 of the drawings. The tubes 3 may be

plain or they may be provided with lateral projections in the form of spiral flanges 4 as shown. The tubes shown in the drawing may be defined or described generically as 5 gilled tubes.

The opposite ends of the tubes 3 of the respective units project through openings 5 and 6 into chambered terminal or head members 7 and 8. The outer walls of these members are provided with openings 10 in opposed relation to the openings 5 and 6 for the purpose of enabling the expanding and upsetting of the ends of the tubes 3 in the openings 5 and 6 and within the chambers 15 of the members 7 and 8 to thereby connect the said terminal or head members to the ends of the tubes.

The openings 10 are closed by screw threaded plugs 12.

20 For the purpose of strengthening the top and bottom walls of the members 7 and 8 I have provided the internally situated oppositely disposed flanges 11 and for the purpose of further strengthening the outer walls 25 of each of the said members and to provide means for contacting with the top and bottom walls 1 of the rectangular channel section I have provided external outwardly projecting flanges 15 which project beyond 30 the heads of the plugs 12. The presence of the flanges 15 with their edges in contact with the top and bottom walls 1 causes the fluid which may be flowing through the channel or conduit within which the apparatus 35 is situated to contact with the tubes 3 and the projecting flanges or gills thereon.

It will be assumed that in the operation of the apparatus one of the fluid media will be delivered through pipes 16 to the 40 terminal or head members 7 from which it will flow downwardly through the tubes 3 to the terminal or head members 8 from which it will be discharged through the discharge pipes 17. However, it will be understood that the passage of the said fluid media through a unit or units may be in the opposite direction. The other media will flow simultaneously through the casing within 45 which the said apparatus is situated transversely of the tubes 3 and will contact with the exterior surfaces thereof. In the construction as illustrated a number of heat exchange units are disclosed as being disposed within the casing and extending across the 50 same but it will be understood that the number may be varied as desired.

For the purpose of connecting together a 60 number of units, which number may be greater or less as desired, I have provided each of the terminal or head members 7 and 8 with pockets 20 adjacent its opposite ends in alignment with one of the rows of tubes 3. The outer side of each of said pockets of each unit is closed by a wall 21 having a depression 22 therein into which extends a

projection 23 from the adjacent wall of the next succeeding unit, when a plurality of units are united and joined together. The walls 21 are provided with openings through which project the screw threaded ends of 70 screw bolts 25 which are secured in openings which extend through the adjacent wall of the terminal or head member of the next succeeding unit. The said units are held and bound together by nuts 26 upon the 75 screw threaded ends of the screw bolts 25.

Each unit is of general rectangular shape in outline and the structure produced by the combining of a plurality of such units is likewise of rectangular outline which permits the use of an inclosing casing of rectangular shape or outline in cross section.

80 The terminal or head members 7 and 8 are of like construction and are standardized as to size, shape and structure. The tubes 85 3 may be of different lengths depending upon the capacity desired. The number of units employed in the construction of an apparatus may vary depending upon the 90 capacity of the apparatus desired.

95 It will be seen that by my invention I have provided means whereby apparatus of any desired capacity may be readily constructed without the necessity of specially designing the same.

Having thus described my invention what I claim and desire to secure by Letters Patent is:

1. In heat exchange apparatus, the combination of a plurality of tubes, chambered 100 terminal members having openings through their inner sides through which the opposite ends of the said tubes extend and within which said tubes are secured and the said members each being provided with means 105 providing access to the interior thereof to enable the upsetting of the ends of the said tubes and each of said members also having a pocket in its opposite ends, which extend transversely thereof, the opposite 110 ends of said pockets being open and the outer side of each of the said pockets being provided with a hole therethrough, substantially as described.

115 2. In heat exchange apparatus, the combination of a plurality of tubes, chambered terminal members secured to the opposite ends of said tubes, the said tubes communicating with the interiors of said members and the outer sides of said members being 120 provided with outwardly extending flanges, and a conduit or passage within which the said heat exchange apparatus is situated and with the top and bottom walls of which the said flanges contact, substantially as described.

125 3. In heat exchange apparatus, the combination of a plurality of heat exchange units, each unit comprising a plurality of tubes, hollow terminal members secured to 130

the opposite ends of said tubes, inlet and outlet pipes, the inlet pipe being connected to one of said hollow terminal portions and the outlet pipe to the other of said hollow 5 terminal portions, and each terminal portion being provided with a pocket at its opposite ends, said pockets opening upon the ends of said portions and the outer side walls of which are adapted to lie against the outer 10 end portions of the adjacent walls of adjacent terminal portions, the said outer end portions being provided with screw bolts which are adapted to project through openings into the said pockets and means for 15 fastening the said screw bolts within said openings.

4. In heat exchange apparatus, the combination of a plurality of heat exchange units, each unit comprising a plurality of 20 tubes arranged in rows in parallel relation with respect to each other and the tubes in one row being arranged in staggered relation with respect to those in the other, hollow terminal portions secured to the opposite ends of said tubes, inlet and outlet pipes 25 communicating with the respective hollow terminal portions of each unit and the outer

side walls of each terminal portion being provided with outwardly extending flanges, each hollow terminal portion being provided with a couple of pockets, one pocket 30 at each end thereof, which pockets open upon the opposite ends of said portion and means upon an adjacent unit projecting into the said pockets and being secured therein 35 to thereby fasten the said units together, and a conduit within which the said apparatus is situated and with the upper and lower walls of which the said flanges contact, substantially as described. 40

5. A standardized terminal member for a heat exchange unit consisting of a hollow member having a series of holes in one side thereof in which the ends of tubes are adapted to be secured and the opposite ends of 45 said member being provided with pockets which extend longitudinally of the said member and open upon the said opposite ends, and the outer sides of said pockets being provided with openings therethrough. 50

In testimony that I claim the foregoing as my invention I have hereunto signed my name this 23rd day of May, 1922.

HANS J. ZIMMERMANN.
